UNITED STATES PATENT OFFICE

PHILIP JORDAN NOEL, OF BOWLING GREEN, KENTUCKY

PISTOL HOLSTER

Application filed July 22, 1930. Serial No. 469,849.

This invention relates to pistol holsters of the type which are adapted to fit into the pocket of a garment, such as a trouser hip pocket.

5 Its object is to provide such a holster of simpler and less expensive construction than heretofore in use, equipped with means for anchoring itself securely in the pocket, with a pouch for carrying the pistol or revolver 10 in a position with the handle or butt pointing away from the middle of the wearer's back.

In the accompanying drawing which shows a form of the invention:

15 Figure 1 is a view illustrating the ease of grasping the pistol when carried in the position mentioned;

Figure 2 is a vertical section end view, showing the holster in the garment pocket and the pistol in the pouch of the holder;

20 Figure 3 is a horizontal section on the line 3—3 of Figure 2;

Figure 4 is a perspective view of the complete device;

25 Figure 5 is a fragmentary elevation of a modification of the holder plate with parts broken away; and

Figure 6 is a section on line 6—6 of Figure 5.

Similar characters refer to corresponding 30 parts in the different figures.

The device is built on a plate 1, of stiff leather or other suitable material. A pair of flexible springs 2—2 are attached by rivets 3—3 securely to plate 1. The springs 35 are preferably of C-shape, but may be given other suitable shapes which will provide the rounded member 4 and be sufficiently long for flexibility.

To plate 1 is attached pouch 5, by means of 40 stitching 6 or other means, of suitable shape for holding the pistol, as indicated in Figure 2.

When thrust into a pocket, springs 2 yield 45 inwardly when rounded members 4 pass the top hem of the pocket and spread laterally below it, anchoring the device securely in the pocket. In Figure 2 the rounded members 4 of the springs are seen stretching the fabric of the pocket 7 outwardly, in such manner 50 that the rounded members would not pass the

hem of the pocket and allow the device to slip out of the pocket, unless the springs were purposely compressed by finger and thumb, or intentional force exerted on the plate 1. In Figure 1 the pocket is shown stretched outwardly on both sides by the springs. Ordinarily, a gun is carried in a hip pocket with the butt pointing toward the middle of the wearer's back. This necessitates reaching for it with the palm of the hand toward the body. But by reason of the more natural position of the arm in reaching to the hip pocket with the back of the hand toward the body, it is preferred in my invention to carry the gun in the position shown in Figure 1, which enables the wearer to grasp the gun and bring it into action much more quickly.

The invention is not intended to be limited to the particular form or details shown and described.

The stitching 6 forms a seam 8 on one side and 9 on the other of the pouch 5, the seam 8 slanting inwardly from the upper end, and is angularly disposed to the side 10 of the 75 plate 1. Thus the barrel 11 of the revolver resting in the pouch 5 will rest in said pouch at a corresponding angle throwing the handle of the revolver above the pocket 7 and pouch 5, the handle 12 being at such an angle that it 80 may be easily grasped for use. The seam 9 conforms to the trigger guard 13 of the revolver 14 and holds the revolver 14 in proper alignment with the seam 8. The plate 1 has a corner 15 which projects above the pocket 85 7. Although the holster will be securely locked in the pocket against any displacement, due to the drawing of the revolver, sufficient force may be exerted on the corner 15 to withdraw the plate without the necessity of compressing the springs 2. The unusual construction of the springs 2 makes this possible, since the rounded corner 4 although 90 locking against ordinary or accidental displacement, will give sufficiently due to the curvature in the bottom portion of the C-shaped spring so that it is possible to remove the holster intentionally without compressing the spring, although it is realized that 95 the springs will be manually compressed most 100

of the time when it is desired to remove the holster and plate to save wear on the pocket.

A modified form of the invention is shown in Figs. 5 and 6 wherein the spring 4 is unsecured at its top portion sliding freely between the pieces of leather 1' and 1''. An eyelet 16 prevents complete removal of the rounded member 4 of the spring 2 from beneath the two pieces 1' and 1'', the spring 2 moving freely in the opening 17 left between the pieces 1' and 1''.

What is claimed is:

A pistol holster comprising a substantially rectangular rigid plate adapted to conform in size and shape to seat in a hip pocket, a pistol holding pocket secured on one face of said plate and a pair of substantially C shaped springs each having a closed loop on each end, said springs secured to said plate one on each side of said pistol pocket and adjacent the top thereof by rivets passing through said end loops and said plate in such manner that said springs normally project beyond the side edges of said plate but may be pressed in toward said edges to permit withdrawal of the plate from a pocket.

In testimony whereof I affix my signature.
PHILIP JORDAN NOEL.
